CLAIM

The ornamental design for a latch handle for a pivoting window sash, as shown and described.

DESCRIPTION

FIG. 1 is a bottom, front, and left side perspective view of a latch body for a pivoting window sash showing our new design;

FIG. 2 is a bottom plan view thereof;

FIG. 3 is a front elevational view thereof, the rear being a mirror image of that shown;

FIG. 4 is a top plan view thereof;

FIG. 5 is a right side elevational view thereof; and

FIG. 6 is a left side elevational view thereof.
